(57) **CLAIM**

The ornamental design for an alligator-shaped trampoline, as shown and described.

DESCRIPTION

FIG. 1 is a perspective view showing my new design for an alligator-shaped trampoline.

FIG. 2 is a top plan view;

FIG. 3 is a bottom plan view;

FIG. 4 is a right side elevational view;

FIG. 5 is a left side elevational view;

FIG. 6 is a rear elevational view; and,

FIG. 7 is a front elevational view.

The broken lines in the drawing are for illustrative purposes only and form no part of the claimed design.
